UNITED STATES PATENT OFFICE.

HALE S. COLEMAN, OF ASHLAND, WISCONSIN.

MECHANICAL TOY.

1,245,089.

Specification of Letters Patent. Patented Oct. 30, 1917.

Application filed July 7, 1917. Serial No. 179,196.

To all whom it may concern:

Be it known that I, HALE S. COLEMAN, a citizen of the United States, residing at Ashland, in the county of Ashland and 5 State of Wisconsin, have invented certain new and useful Improvements in Mechanical Toys; and I do hereby declare the following to be a full, clear, and exact description of the invention, such as will enable 10 others skilled in the art to which it appertains to make and use the same.

My invention has for its object to provide a mechanical toy; and, to this end, it 15 consists of the novel devices and combinations of devices hereinafter described and defined in the claims.

In the accompanying drawings, which illustrate the invention, like characters indicate like parts throughout the several views.

20 Referring to the drawings,

Figure 1 is a view of the toy, partly in side elevation and partly in central vertical section, with some parts broken away; and

25 Fig. 2 is a horizontal section taken on the irregular line 2—2 of Fig. 1.

The numeral 3 indicates two vertically spaced annular base sections supported at diametrically opposite points on a hoop-like frame 4. The toy may be turned and 30 supported on either of its base sections 3. Located between the two base sections 3, is an upright rod 5 having each of its ends bent to form a pair of diametrically opposite crank arms 6, provided with eyes 7 in 35 their outer ends. The intermediate portion of the rod 5 is also bent to form an annular eye, in which is intermediately secured a horizontal bar 9. On each end of the bar 9, is a figure 10 (as shown, a boy holding a 40 flag) secured by a horizontal pivot 11, in the form of a nail or screw, for turning movement in a vertical plane, and the lower portions of said figures have sufficient weight to keep the same in upright positions.

Each pair of crank arms 6 is secured to the adjacent base section 3, at the axis thereof, by a pair of flexible non-elastic connections 12, as shown, in the form of cords.

50 These cords 12 have their inner ends secured in the eyes 7 of the crank arms 6 and their outer ends are extended through axial bores 13 in the base sections 3 and which bores also extend radially through the frame 4. 55 The outer ends of the cords 12 are knotted at 14, after passing the same through the

bores 13, to anchor the same. Cavities 15 are formed in the bottoms of the base sections 3 to receive the knots 14, so that said base sections will rest evenly upon the support on which they are alternately placed. The pairs of cords 12 have such slack, that the one pair can be twisted without placing the other pair under strain.

The twisted pair of cables 12 affords the 65 mechanical power of gravity to revolve the whirling parts of the toy, and when said toy is turned, so that the twisted pair of cables 12 is uppermost, said cords, under the weight of the rod 5, bar 9 and figures 70 10, acting on the connected pair of crank arms 6, impart a whirling movement to said rod, bar and figures. This movement of the whirling parts of the toy, acting through the lowermost crank arm 6, will twist the 75 connected pair of cords 12 simultaneously with the untwisting of the uppermost pair thereof.

When the uppermost pair of cables 12 is 80 untwisted, the whirling of the movable parts of the toy stops. Then by turning the toy so that the same is supported on its other base section 3, which brings the pair of cords 12, thus twisted, uppermost, the 85 movable parts are again started to whirl.

Secured to each base section 3, is a cylindrical casing 16, which extends axially inward and has in its inner end a small aperture through which the adjacent end of the rod 5 projects. These casings 16 90 hold the rod 5 against radial movement, but with freedom for endwise movement therethrough, and completely inclose the crank arms 6 and pairs of cords 12.

What I claim is:—

1. A mechanical toy comprising a frame, an upright rod having cranks at its ends, an object carried by the rod, and flexible non-elastic pairs of connections between the crank ends of the rod and opposite points 100 on the frame, said pairs of connections having such slack that the one pair can be twisted without placing the other pair under strain, whereby when the twisted pair of connections is uppermost, the same will 105 impart a whirling movement to the rod and object carried thereby and twist the lowermost pair of connections.

2. A mechanical toy comprising a frame, an upright rod having cranks at its ends, 110 a bar intermediately secured to the intermediate portion of the rod, a figure pivoted

- to each end of the bar for pivotal movement in a vertical plane and weighted to stand in an upright position, and flexible non-elastic pairs of connections between the 5 crank ends of the rod and opposite points on the frame, said pairs of connections having such slack that the one pair can be twisted without placing the other pair under strain, whereby when the twisted pair 10 of connections is uppermost, the same will impart a whirling movement to the rod, bar, and objects carried thereby and twist the lowermost pair of connections.
3. A mechanical toy comprising a pair 15 of vertically spaced base sections and a frame connecting the same, an upright rod located between the base sections and having cranks at its ends, a bar carried by the rod and having figures mounted thereon, 20 and pairs of cords connecting the crank ends of the rod to the base sections, said pairs of cords having such slack that the one pair can be twisted without placing the other pair under strain, whereby when the toy 25 is supported on the base section to bring the twisted pair of cords uppermost, the same will impart a whirling movement to the rod, bar and figures and twist the lowermost pair of cords.
- 30 4. A mechanical toy comprising a pair of vertically spaced base sections and a frame connecting the same, an upright rod located between the base sections and having cranks at its ends, a bar carried by the rod and having figures mounted thereon, pairs of 35 cords connecting the crank ends of the rod to the base sections, said pairs of cords having such slack that the one pair can be twisted without placing the other pair 40 under strain, whereby when the toy is supported on the base section to bring the twisted pair of cords uppermost, the same will impart a whirling movement to the

rod, bar and figures and twist the lowermost pair of cords, and casings secured to 45 the base sections and covering the crank ends of the rods and the pairs of cords.

5. A mechanical toy comprising a frame, an upright rod having cranks at its ends, a bar carried by the rod and having figures 50 mounted thereon, and pairs of cords connecting the crank ends of the rod to opposite points on the frame, said pairs of cables having such slack that the one pair can be twisted without placing the other pair under strain, whereby when the twisted pair 55 of cables is uppermost, the same will impart a whirling movement to the rod, bars and figures and twist the lowermost pair of cords.

6. A mechanical toy comprising a pair of vertically spaced base sections and a frame connecting the same, an upright rod located between the base sections and having each of its ends bent to form a pair of crank 65 arms and having its intermediate portion bent to form a loop, a bar intermediately secured to the loop in the rod, figures mounted on the bar, pairs of cords connecting the crank arms to the base sections, said pairs 70 of cords having such slack that the one pair can be twisted without placing the other pair under strain, whereby when the toy is supported on the base section to bring the twisted pair of cords uppermost, the same 75 will impart a whirling movement to the rod, bar and figures and twist the lowermost pair of cords, and casings secured to the base section and covering the crank arms and pairs of cords.

In testimony whereof I affix my signature in presence of two witnesses.

HALE S. COLEMAN.
